UNITED STATES PATENT OFFICE

2,438,603

TOY LOADING STATION

Oscar P. Erhardt, West Haven, Conn., assignor to
The A. C. Gilbert Company, New Haven, Conn.,
a corporation of Maryland

Application February 22, 1944, Serial No. 523,411

21 Claims. (Cl. 46—40)

1

This invention relates to a toy railway accessory in the nature of a unitary crane station which may be powered and controlled electrically if desired for loading toy flat cars automatically with imitative logs or with any other toy articles fashioned to imitate railway freight materials.

A crane station of this general nature is disclosed in a copending application, Serial No. 407,769, now United States Patent No. 2,373,271, granted April 10, 1945, owned by the assignee of the present application, and certain features common to the disclosures of both applications are claimed in the said copending application.

One object of the invention is to provide a low cost apparatus of this nature in unitary form which shall be sturdy and durable and proof against easily getting out of order. A related object is to shield the working parts effectively by means of their structural disposition relative to the supporting frame structure of the apparatus.

Another object is to provide an improved mechanism for transferring toy logs or other toy load articles one at a time to the carrying support of a crane trolley preceding an excursion of the latter for conveying the toy logs or other toy articles from a supply thereof to a position where they may be loaded upon a toy railway car. A related object is to make use of chucker mechanism, additional to all mechanism which travels with the crane trolley, for lodging the toy load in the retaining hold of the trolley, which chucker mechanism according to the present improvements remains at a permanently fixed point in the crane station during travel of the crane trolley.

A further object is to provide a unidirectional actuating element for causing the crane trolley to perform a reciprocative excursion and, also automatic cycle controls operative to terminate the unidirectional movement of such trolley actuating element after the completion of each excursion of the crane trolley.

A still further object is to place the power drive for the crane trolley and a separate actuator for the chucker mechanism both under electrical control managed at a point remote from the crane station.

A particular object is to provide a crane trolley with a toy log clutch claw adapted to exert three-point clutching pressure against the log.

Other objects are to conceal a power motor for the apparatus within a toy controller house incorporated in the framework of the crane sta-

2

tion, and to arrange a base platform of the station to serve as a bin whose rear or receiving side is disposed to receive logs from toy self-dumping supply cars such as disclosed in U. S. Patent No. 2,356,280, and in a copending application Serial No. 469,046, filed December 15, 1942, both owned by the assignee of the present application, while at the other side of the crane station the logs derived from the dumping car or any other suitable source are finally loaded by the crane station one by one at a delivery location some distance from the supply car such as onto another car standing at the front or opposite discharging side of the crane station.

The foregoing and other objects of the invention will more fully be understood from the following description of a practical and successful embodiment of the invention, in which description reference is had to the accompanying drawings wherein:

Fig. 1 is a side view of a complete car loading toy crane station incorporating the present improvements showing its conveyor trolley ready to start a log carrying excursion.

Fig. 2 is a plan view taken partly in section on the horizontal plane 2—2 in Fig. 1 with certain parts broken away to expose underlying structure.

Fig. 3 is a view similar to Fig. 2 showing the crane conveyor trolley in the act of dropping a toy log onto the railway car after a half cycle of automatic crane operation.

Fig. 4 is a view taken mostly in section on the vertical plane 4—4 in Fig. 3 looking in the direction of the arrows.

Fig. 5 is an outside view of the front or car loading side of the crane station with a toy flat car standing on the toy railway track in position to be loaded with logs.

Fig. 6 is an enlarged isometric view of the cycle controlling electric switch detached from its supporting structure.

Fig. 7 is an enlarged isometric view of the conveyor trolley.

Fig. 8 is an enlarged isometric view of the log chucker removed from its place beneath the bin platform.

Fig. 9 is a diagram of the electric circuit connections.

The frame structure of a log loading station embodying the present invention may be fanciful in appearance and is represented herein as a skeletonized structure designated 10 preferably resembling structural steel work consisting of four upright channel girders or lattice posts 11

positioned at the corners of a base area that is spanned at a low point by a doubly inclined bin platform 12 containing at the lowest point of its trough-like shape spaced slots 13 that are nearer together than the length of a toy log 16. The two front posts stand beside toy railroad tracks 14 on which a toy flat car 15 is shown in endwise view positioned to be loaded automatically with the logs 16 taken one at a time from a supply reposing on bin platform 12 which may be referred to as a repository for the logs. The tops of posts 11 are spanned by a roof structure 20 which overhangs platform 12 and projects over the toy tracks 14 and also serves to support an imitative crane operator's house 21.

On the roof structure 20 within house 21 there is fixedly mounted an electric motor 22 having an armature shaft 23 fixedly carrying a pinion 24 that drives a train of reduction gears 25 journaled in spaced bearing plates 26 that are fixed in relation to the stator of motor 22. The slow gear of reduction train 25 together with a large crank wheel 31 are rotatably fixed on vertical shaft 30 that is journaled in plates 26. Wheel 31 thereby is rotated counterclockwise in Figs. 2 and 3 on occasions by motor 22.

Crank wheel 31 carries a lug 32 of insulating material for operating electric switch contacts, which lug may be fixed on wheel 31 by rivets 33, or otherwise, in a manner to project radially beyond the periphery of the wheel. In the path of lug 32 a spring leaf type of conductive electric contact 34 is secured by rivets 35, or otherwise, to a base bar 36 of insulating material that is rigidly mounted on roof structure 20, as by means of an angle bracket 37 which may be fixed on base bar 36 by rivets 38 and fixed on roof structure 20 by rivets 39, or otherwise. For circuit-making contact with the movable end of leaf-spring contact 34 there is also secured on bar 36 by rivets 41, or otherwise, a stationary circuit terminal 49. Binding posts 45 and 46 are mounted on and in insulated relation to roof structure 20 and serve as convenient points of connection for lead wires 47 and 48 and other circuit connections diagrammed in Fig. 9.

At an intermediate level between bin platform 12 and roof structure 20 there is incorporated in fixed relation to frame 10 an inclined runway 54 which may consist of two laterally spaced rigid stationary tracks 55 extending from the front nose beam 19 of roof structure 20 in Figs. 1 and 4 to a relatively lower point above bin platform 12. At this point the angle strips which serve as tracks 55 are bent to extend upward to a fixed anchorage at 52 on frame 10. A log conveying trolley 56 is equipped with four wheels 57 having axles 53 and spaced to roll on tracks 55 when trolley 56 is hauled forwardly upward on its runway 54 and then released to return to its starting point. This hauling of trolley 56 is performed by a cable cord 58 tied to an anchorage 60 on crossbar 59 of the trolley frame structure and runs around a sheave 61 of the pulley block 62 whose anchor hook 63 swingably engages an aperture 64 in the nose beam 19 of the roof structure. The other end of cable cord 58 is tied to a swivel eye 65 that pivotally connects to a stud 66 which is fixed in the rim of crank wheel 31 and projects downward therefrom as shown in Figs. 1 and 4.

The aforementioned frame of trolley 56 includes side plates 67 of like shape hung from the wheel axles 53 and secured in rigid spaced relation by the aforesaid cross bar 59 as well as by

an additional cross brace 68. Each side plate 67 is shaped to present downward an inverted convex edge or seat 69 against which one of the logs 16 may be pressed and retained on occasion by a swingable clamp plate 70 that is swingably supported between side plates 67 by means of cross spindle 71 carried by the side plates. A downward projecting, log clamping, bowed tongue 72 is caused to press against a toy log by the urge of an axially expansible spring coil 73 against clamp plate 70 in the direction of seats 69. Spring coil 73 loosely surrounds shank 74 of a log releasing plunger 75 which passes through and has a slide bearing fit in each of bar 59 and cross brace 68 and which has free clearance through an aperture in clamp plate 70. Spring 73 is always under axial compression between clamp plate 70 and cross brace 68 thereby constantly urging the clamp plate toward the log seats 69 and against stop ears 76 turned inward from each side plate 67 as shown in Figs. 1 and 7. In Figs. 4 and 7 it is shown that thrust ears 76 are nipped up out of the metal of shank 74 for enabling the clamp plate 70 to relay the forward thrust of spring 73 to the release plunger 75 and conversely for enabling a pressure, directed rearwardly on plunger 75, to force clamp plate 70 in a direction away from log seats 69 as shown in Fig. 4. The extreme rear end of shank 74 may also be nipped to provide thrust ears 77 thus preventing shank 74 from being accidentally pulled forward out of engagement with cross brace 68.

From the foregoing description it will be seen that the combined seat 69 and clamp plate 70 form in effect a downward opening claw giving admittance to a toy log that may be lifted from below into the clutch of this claw. Stop ears 79 turned inward from the bottom edges of trolley sides 67 underlie tracks 55 with sliding clearance and prevent lifting of the trolley from the track.

It is the function of the swingable chucker 82, shown detached in Fig. 8, to lift a log from the bin platform 12 into the clutch of the log holding claw formed by seats 69 and clamp plate tongue 72. For this purpose the working head of this lifter member or chucker 82 is composed of a light weight metallic strip 83 bent to U-shape having its upturned ends notched in V-form at 84 and adapted in rising from the retracted position shown in Fig. 4 to the elevated position shown in Fig. 1 to pass through the aforesaid slots 13, respectively, in the bin platform. Claw 69, 70 is normally stationed directly above the chucker head 83 by a stop 85 upstandingly fixed on tracks 55. The chucker head 83 is carried at the front end of two spaced hinge arms 88 fixed in relation thereto and each hinge arm at its rear end 89 loops about a hinge pin 90 supported at each of its ends in a stationary bearing bracket 91 secured to frame 10 by screws 92, washers 93 and retaining nuts 94. Hinge pin 90 may be pinched to form the thrust ears 95.

For actuating the chucker 82 a crank pin rod 96 is welded or otherwise fixedly secured to the hinge arms 88 in parallel relation to strip 83 and projects at one side of the chucker to be pivotally engaged by the looped end 97 of a vertical lifter rod 98 on whose upper end is fixed a magnetic plunger 99 operating within the field of pull of an electric solenoid 100 whose top end is fixedly secured to a mounting bracket 101 riveted or otherwise fastened to the frame 10 at 102.

In the diagram of connections in Fig. 9, a 75 duplex, momentary or self opening, manual push

button switch is indicated as a whole by 106 having two supply main contacts 107, a motor circuit contact 108 and a solenoid circuit contact 109. Circuit can momentarily be made through 107, 108 by pushing the self-lifting contact bridging button 110, and can be made through 107, 109 by pushing a like button 111. Buttons 110, 111 are optionally operable so there is no restriction in the sequence or relationship in which the motor and solenoid circuits can manually be made or broken.

Fig. 4 indicates in broken lines that another toy flat car 15' similar to car 15 may ride on tracks 14' to a position adjoining the rear edge of the bin platform 12 so that the car 15' can act to dump its load of logs 16 on the platform 12 on which they will by gravity roll down to the full line positions shown in Fig. 4 ready to be lifted by the chucker 82 one by one into the grasp of the carrying claw of crane trolley 56. Car 15' may be constructed in accordance with the aforesaid Patent 2,356,280 or copending application Serial No. 469,046 or otherwise. The unloading and delivering of logs at one side of the crane station followed by the sequential pickup and delivery of the logs deposited thereon to an empty toy car at the other side of the crane station produces a logical chain or continuity of imitative industrial operations that enhances the appeal of the toy to the imagination of older boys because of its realism and the greater fullness of automatic performance wherein the operator of the crane station need never touch with his hands the toy logs or other toy articles in order to accomplish their unloading from one car, followed by their transfer and reloading onto a different car.

Reviewing the operation of the crane station with particular reference to the electric wiring diagram of Fig. 9, the crane trolley 56 will normally stand in its position shown in Figs. 1, 2 and 5 with the chucker 82 lowered against stop 81 as shown in Fig. 4. Assuming that the operator presses the self returning push button 111 of momentary switch unit 106, solenoid 100 will thereby be energized and draw the chucker 82 smartly upward until its movement is abruptly halted by striking the bottom of platform 12 causing the chucker to lift and catapult upward whatever log 16 is directly over it thus to fling and lodge such log between claw seats 69 and the yieldable leaf-spring clamp 72 as shown in Fig. 1. The operator may now push self returning button 110 of momentary switch unit 106 temporarily closing circuit through motor 22 which in the meanwhile has been standing de-energized because the normally self-closing contacts 34, 40 have been held open by the crank wheel lug 32. Immediately the crank wheel starts to rotate slowly counterclockwise in Figs. 2, 3 and 9 promptly releasing spring leaf contact 34 from the lug 32 whereupon the former automatically flexes into conductive engagement with contact terminal 40 as shown in Figs. 3 and 6. The circuit through the motor is now maintained closed even when the operator releases switch button 110 breaking circuit through 108. Thus crank wheel 31 will continue to be rotated by motor 22 from the position in Fig. 2 to the position in Fig. 3 during which half revolution of wheel 31 the draft cable 58 is pulled to haul crane trolley 56 forward and upward on the runway 55 until its plunger head 75 bumps against the nose beam 19 and thus causes the claw clamp 72 to open against the resistance of spring 73 freeing

5 the log 16 which thereupon drops onto the toy car 15 as it is shown in the act of doing in Fig. 4. Continued counterclockwise rotation of crank wheel 31 will pay out cable 58 permitting the weight of trolley 56 to cause it to coast backward down the runway 55 to its starting position shown in Fig. 1 wherein it is arrested by the track stop 85. At this time the crank wheel lug 32 has arrived at its starting position shown in 10 Figs. 2 and 9 and acts on leaf contact 34 to break the circuit to the motor whereupon all parts come to rest and the crane station is ready to repeat the automatic cycle of action described.

It may be noted that the present improvements 15 provide a construction in which different parts of the apparatus may easily be removed as a unit for replacement or repair without disturbing or disassembling other units of the apparatus. For example the crane trolley 56 may be removed 20 without disturbing motor 22 or chucker 82 and the same is true of each of the motor and the chucker.

It will be realized that many forms of the invention are possible which may vary as to the 25 size and shape and relative disposition of the structural parts referred to in the appended claims, wherefore the language of the claims is intended to cover and apply to all substitutes and equivalents fairly comprehended by the terms 30 used in the claims.

I claim:

1. In a toy crane station for transferring toy articles from a repository to a delivery location some distance therefrom, the combination of, a 35 repository for toy load articles in said station, a crane track in said station, a trolley supported by said track to perform an article conveying excursion therealong away from and back to an article receiving position proximate said repository, and 40 means operative to transfer a toy load article from said repository to said trolley constructed and arranged to remain at said repository while said trolley performs its said excursion.

2. In a toy crane station for transferring toy articles from a repository to a delivery location, the combination of, a repository for toy load articles at a relatively low level in said station, a crane track at a relatively high level in said station, a trolley supported by said track to perform 45 an article conveying excursion away from and back to an article receiving position above said repository, and mechanism separate from said trolley including a lifter member movably anchored in a permanent location relative to said 50 repository to be operable at said location in a manner to transfer a toy load article from said repository to said trolley.

3. In a toy crane station, the combination defined in claim 2, in which the said repository is 55 constructed and shaped to shed toy logs one at a time toward a relatively low point thereof, and the said lifter member is movable upward toward the said trolley from said low point in the repository.

4. In a toy crane station, the combination defined in claim 2, in which, the said lifter member is normally positioned beneath the said repository and said repository includes a sloping platform containing an aperture at the foot of its slope too small to admit one of the said toy load articles therethrough while large enough to admit the said lifter member therethrough.

5. In a toy crane station, the combination defined in claim 2, in which the said trolley includes a claw device extending downward below

the said track constructed and arranged to receive from the said lifter member and retainingly grasp one of the said toy articles.

6. In a toy crane station, the combination defined in claim 2, in which the said trolley includes a spring claw device opening downward toward the said lifter member, and said lifter member is constructed and arranged to rise into sufficient proximity to said claw device to deliver into the retaining grasp of the latter one of the said toy articles.

7. In a toy crane station, the combination defined in claim 2, in which the said trolley includes a claw constructed and arranged to receive from the said lifter member and automatically to clutch one of the said toy articles, together with instrumentalities operative to cause said claw to open and release said toy article from its clutch consequent upon the arrival of said trolley at a predetermined point along said track, said instrumentalities including cooperatively engaging elements in part carried by said trolley and in part stationed in relation to said track.

8. In a toy crane station, the combination defined in claim 2, in which the said crane track is inclined upward from the said article receiving position of the said trolley to the said article discharging position of the latter, thereby enabling said trolley to coast from its latter said position to its first said position.

9. In a toy crane station, the combination defined in claim 2, in which the said trolley inclined to cause the said trolley to coast downward thereon in one direction, together with a trolley impelling crank device mounted to revolve unidirectionally, and a cable connected to said trolley and also so connected to said crank that alternate half revolutions of the latter first haul said trolley forward up said inclined track and then permit the trolley to coast backward down said inclined track.

10. In a toy crane station, the combination defined in claim 2, together with an electric motor, a single revolution crank device connected to be rotated by said motor repeatedly in the same direction, draft connections so operatively relating said crank device and the said trolley that one revolution of the former causes the latter to complete its said excursion of travel, and electric circuit controlling means for said motor arranged to be actuated mechanically by said crank device in a manner automatically to stop said motor at the end of one full revolution of said crank device.

11. In a toy crane station, the combination defined in claim 2, together with an electric solenoid for actuating the said lifter member having a magnetic plunger reciprocative in a vertical path mechanically coupled to said member in a manner to pull the latter upward.

12. In a toy crane station, the combination defined in claim 2, together with an electro-magnetic actuator mechanically connected to the said lifter member in a manner to force the latter upward, and an electric motor mechanically connected to the said trolley in a manner to impel the latter intermittently in at least one direction, separate electric circuits containing said actuator and said motor, and independently operable electric switches electrically connected to control said separate circuits and juxtaposed at a common control station remote from the crane station.

13. In a toy crane station, the combination de-

fined in claim 2, in which the said trolley includes a claw device projecting downward toward the said repository, and the said lifter member comprises a chucker, together with an actuator operative to impel said chucker upward in a manner to catapult a toy load article into the retaining clutch of said claw device.

14. In a toy crane station, the combination defined in claim 2, in which the said trolley includes a depending claw for clutching one of the said toy load articles, said claw including a retractable clamp with spring means urging said clamp in a direction to clutch said toy load article.

15. In a toy crane station, the combination defined in claim 2, in which the said trolley includes a depending claw for clutching one of the said toy load articles, said claw including a retractable clamp with spring means urging said clamp in a direction to clutch said toy load article, together with cooperative instrumentalities in part carried by said trolley and in part stationed at a predetermined point along said track operatively related to said clamp in a manner to retract the latter in a direction to release said toy load article and let it fall from said trolley when the latter reaches said predetermined point in its travel along said track.

16. In a toy crane station, the combination defined in claim 2, in which the said trolley includes a depending claw for clutching one of the said toy load articles, said claw including a retractable clamp with spring means urging said clamp in a direction to clutch said toy load article, together with a buffer stationed in fixed relation to said track, and a clamp retracting device projecting toward said buffer from said trolley operative when forced against said buffer by the travel of said trolley to overcome said spring and retract said clamp thereby to release and let fall said toy load article.

17. In a toy crane station, the combination defined in claim 2, in which the said lifter member includes a chucker head shaped to cradle a toy log, and an arm pivotally mounted to swing beneath the said repository carrying said chucker head at the free end thereof.

18. In apparatus for automatically handling toy logs, a repository platform structure providing an elongated channel adapted to seat a toy log lengthwise thereon and having two apertures spaced apart lengthwise of said channel, and a toy log lifting member beneath said platform mounted to move up and down and having two upstanding arms fixed together in a manner to be elevated in unison through said apertures respectively, thereby to engage simultaneously with points on a toy log spaced apart lengthwise thereof while said log rests in said channel and overlies both of said apertures, whereby said arms lift said log from said channel and prevent it from tipping.

19. In apparatus for handling toy logs, a crane trolley including a wheeled carriage frame and a log clutching claw composed of laterally separated concave claw seats facing in a common horizontal direction carried by said trolley frame in fixed relation thereto, and a clamp member having a concave surface facing toward said concave seats located laterally therebetween, whereby three-point clutching pressure is exerted against said log when the latter is held in said claw.

20. A toy crane station embodying in combination, an elevated frame structure, a toy crane

controller house atop said structure, a crane track supported on said frame below said controller house, a crane trolley riding on said track, a motor in said controller house, and a crank wheel pivotally supported to rotate on a vertical axis between said controller house and said crane track, said crank wheel having connections to transmit power from said motor to said trolley.

21. A toy crane station as defined in claim 19,

in which the said crank wheel connections include a flexible return cable extending from the said crank wheel to the said trolley, together with a sheave anchored on the said frame structure occupying and holding the bight of said cable at a distance from both said crank wheel and said trolley.

OSCAR P. ERHARDT.

Certificate of Correction

Patent No. 2,438,603.

March 30, 1948.

OSCAR P. ERHARDT

It is hereby certified that errors appear in the printed specification of the above numbered patent requiring correction as follows: Column 7, line 33, claim 9, for "trolley in—" read *crane track is*; column 9, line 9, for the claim reference numeral "19" read *20*; and that the said Letters Patent should be read with these corrections therein that the same may conform to the record of the case in the Patent Office.

Signed and sealed this 8th day of June, A. D. 1948.
